UNITED STATES PATENT OFFICE.

RUDOLPH LIEBMANN, OF ALLENTOWN, PENNSYLVANIA.

DESIGN FOR A PICTURE-FRAME.

SPECIFICATION forming part of Design No. 23,469, dated July 17, 1894.

Application filed June 19, 1894. Serial No. 515,071. Term of patent 3½ years.

To all whom it may concern:

Be it known that I, RUDOLPH LIEBMANN, a citizen of the United States of America, residing at Allentown, in the county of Lehigh and State of Pennsylvania, have invented and produced a new and original Design for Picture-Frames, of which the following is a specification, reference being had to the accompanying drawing, showing a face view thereof.

o The design illustrated in said drawing consists essentially in the ivy vine *a* bent to form the substantially heart-shaped opening or sight *b*. The lower terminals of the vine form the feet or rests *c c* of the frame. The stems

or twigs projecting from said vine in various directions bear ivy leaves *d d* surrounding and conforming to the heart shaped sight or opening.

What I claim as new is—

The design for a picture frame, substantially as shown and described.

In testimony whereof I affix my signature in the presence of two witnesses.

RUDOLPH LIEBMANN.
